FRANCIS H. RICHARDS, OF HARTFORD, CONNECTICUT, ASSIGNOR, BY MESNE ASSIGNMENTS, TO AMERICAN TYPOGRAPHIC CORPORATION, A CORPORATION OF NEW JERSEY.

ART OF MAKING TYPES AND TYPE-BARS.

No. 919,237.

Specification of Letters Patent.

Patented April 20, 1909.

Application filed April 16, 1901, Serial No. 56,165. Renewed March 10, 1909. Serial No. 482,570.

To all whom it may concern:

Be it known that I, FRANCIS H. RICHARDS, a citizen of the United States, residing at Hartford, in the county of Hartford and State of Connecticut, have invented certain new and useful Improvements in the Art of Making Types and Type-Bars, of which the following is a specification.

This invention relates to the art of making types and typebars, and especially to a method of making from a solid blank or bar of metal a typebar adapted for use in the typographic art for printing a line of characters; and has for an object to provide an improved method of producing these, wherein there will be formed a space adjacent to each type-block and the die will be caused to work upon the type-block, finish the type and continuing its pressure reduce the type-face to a common plane and at the same time justify the formed type lengthwise of the bar.

Many efforts have been made to produce from a mass of type-formable material by the action of a die a type suitable for use in and which would satisfactorily meet the requirements of the typographic art, in point especially of sharp definition and durability, and to combine a number of types so formed in a line of composed types or type faces in the endeavor to produce a typebar that would satisfy the demands of the art for successful commercial application. It is to be borne in mind in the manufacture of typebars, that some of the types of those used for forming the various characters of ordinary composition are more readily formed than others—that is, less work is performed by the dies in producing certain types than in producing others. In other words, the material will need to be subjected to a less number of operations in some instances than in others, depending upon the particular type which is to be produced, and if the type-forming operation is carried beyond the stage in which the material has assumed the condition of a finished type the tendency of the stresses induced by further action of the die is, if a path of escape for the surplus metal be not provided, to mar or distort the type within the die cavity. The line, also, of least resistance to flowage of the metal under the die may be, and almost invariably is, in a direction such that this movement, if not properly con-

trolled, results in the tipping or displacement of the adjacent type. In an organized system of forming composed types along a typebar in which the various elements involved in the type-forming operation—for example, the extent of the preliminary roughing-out of the type-blank, the amount of feed movement of the die and the blank against each other, the concurrent subsidiary motion, if there be such, the amount of surplus material to be removed by the die, etc.—are not adapted to each individual type to be formed, the result is generally an unsatisfactory typebar and one ill-fitted to meet the demands of the art.

The preliminary isolation and trimming of the type-blanks in the method of type-forming outlined above is adapted to the formation of a series of composed types having a common alinement, since the flowage of material from the type-blank during and subsequent to the formation therefrom of an early-formed type may readily take place in a direction of an adjacent cross slot. Such a method of forming types and typebars is set forth in my application Serial No. 41,830, filed on January 2, 1901. In such application the feature of reducing each of the types to a common plane after its formation is claimed.

In carrying out my present invention, setting off the type-blanks before the dies are brought into action may be avoided, and I preferably subject each type-formable portion of the blank to repeated actions, which, for the purpose of producing symmetrically-formed types are preferably alternated from side to side of the mass. These repeated actions result in the gradual reduction of the mass to shape and are of such character that they operate to strengthen and finish the base portions of the block where the latter connects with the body of the typebar-blank and to condense and compact the impression and other faces of the type, besides operating to satisfactorily fill the angular portions and hair-line spaces of the die cavity. The excess or surplus material is caused or forced to flow laterally or crosswise of the blank—that is, in a direction away from an adjacent type—and for the purpose of more effectually protecting this latter type from the material subjected to the action of the working die I

preferably utilize a retaining wall at the side of the die for the purpose of confining the material and controlling its direction of flow.

To enable an early-formed type to be carried downward in the bar and for the purpose of obviating any tendency on the part of the type-forming die during this operation to mar or destroy the type block or blank within the cavity of the die, I may, according to 5 one mode of practicing my present invention, subject the type-blank to a preliminary treatment to remove a portion at least of the excess material from the upper edge thereof, or according to another mode and to the 10 same end, provide a line or path of least resistance along which flowage can take place during the descent of the die, the degree of resistance offered to the movement of the die in this case being also insufficient to cause 15 the marring or destruction of the formed type and type-block.

It is evident, in so far as concerns the sinking of the type, that it is immaterial whether a type-separating space be formed in advance of the type or not. In fact, if such 20 space is not formed until after the completion of the type-block additional support will be afforded by the integral connection with the stock of the blank, assisting by the existence 25 of this support the production of a satisfactory type. That is to say, to secure the benefits of this support this space may be made simultaneously with the production of the 30 type-block, or the space may be made subsequently to the completion thereof.

In the drawings accompanying the present specification, Figures 1 and 2 are, respectively, a plan and side elevation of a typebar made according to my present method. 40 Fig. 3 is a perspective view upon a somewhat larger scale of a portion of a typebar-blank provided with a number of types and illustrates one mode of carrying out my present invention. Fig. 4 is a vertical, longitudinal, 45 sectional view upon a greatly enlarged scale of a portion of a typebar-blank, illustrating in a diagrammatic way another mode of carrying out my present invention. Fig. 5 is a view similar to Fig. 4, indicating another 50 step in the mode set forth in Fig. 4; this figure represents a space-forming instrumentality which operates to produce a type-separating space subsequently to the completion of the type-block. Fig. 6 illustrates still another mode of carrying out the present invention, in which the space in advance of the 55 type is formed simultaneously with the formation of the type and by an instrumentality which constitutes an integral part of the type-forming die. Fig. 7 is a view similar to the other figures on that sheet, but shows a mode of carrying out the present invention in which a support in advance of the type-block is afforded by the same tool which 60

65 serves to make the forward space prior to the

operation of the type-forming die. Fig. 8 is a sectional elevation illustrating a die-wheel, a space-forming tool, and blank-feeding means coöperating with the typebar-blank, the scale of this figure being somewhat 70 smaller than that to which Figs. 1 and 2 are drawn.

Similar characters of reference designate like parts in the various figures of the drawings.

In carrying out my present improvements the type, it may be stated in a general way, results from the operation of a suitable type-forming die upon a blank forced one against the other to cause the penetration of the latter by the die, the carrying down of the impression face of the completed type to a common plane, and the justification of the type lengthwise of the bar under pressure.

The blank, designated in a general way 85 throughout the present specification and drawings by B, is of some material suitable for the purpose—as, for instance, type-metal of proper composition wrought into the requisite or desired shape in some suitable 90 way—for example, by casting, rolling, or otherwise. I have found, however, that a process for so operating upon the material as to produce a substantially wrought blank as distinguished from a condition resulting from 95 the casting of the same, or at least a blank having that portion or those portions wrought which are concerned in the formation of the several type-blocks, is best suited for carrying out the present improvements. 100 Moreover, the blank upon which the successive types are to be formed may be a continuous ribbon or rod, or it may be in the form of separate pieces each having a length substantially equal to the length of the finished 105 typebar.

In effecting the penetration of the material of the blank by the die it is immaterial whether the movement, which I may designate a transverse feeding movement, is imparted to the blank or die, or to both, but I find it convenient to feed the blank against the die and have therefore represented in a conventional way in Fig. 8 a carriage W suitably mounted and adapted to have a step-by-step longitudinal motion to bring successive portions of the edge of the blank B supported in a blank or work holder V thereon under the dies. This blank-holder is mounted on the carriage to have a to-and-fro motion transverse to the direction of movement of the carriage toward and away from the dies, there being in the construction shown a rock-lever 12 operated from some suitable means for effecting the movement of the blank toward and away from the dies. A spring 13 or a plurality of the same is provided, as shown, for returning the blank-holder.

In one mode of carrying out my present 130

invention that edge of the blank on which the types are to be formed is beveled, as shown in Fig. 3, so as to taper toward the faces of the type and present, thus, to the compressing 5 action of the die during the type-forming operation a type-formable body increasing in cross-sectional area from the face to the base thereof transversely of the bar. If the type-blank is isolated from its fellows by 10 cross-slitting the edge of the typebar-blank, a blank is thus formed from which, when the blank is under the compression of the die, flowage may take place lengthwise of the typebar-blank. This particular mode of 15 preliminary forming and isolating a type-blank forms no part of the present invention, the same being set forth and claimed in the before-mentioned application, Serial No. 41,830.

20 The type-forming operation may be carried out in any proper manner, but, while hand-operated tools may be employed for the purpose, suitable mechanism will ordinarily be used. Any proper type-die may 25 be employed, and this may be mounted in any desired manner, though I prefer to support one or more type-dies, such as *d*, on a carrier, such as *D*, which carrier may be secured to a shaft, such as *2*, having a movement of 30 revolution about another axis not shown, and also a movement of rotation about its own axis, the resulting movement of each die when its carrier is rotating and revolving being a cycloidal one.

35 The rectilinear transverse feeding movement of the die and blank relatively to each other is not the only movement utilized in carrying out my present improvements for facilitating the filling of the die cavity, for 40 disposing of the excess or surplus material separated or sheared from the type-blank or type-block during the type-forming operation, and for producing a compact and dense condition of the various surfaces, but in combination with this movement there is a relative subsidiary motion imparted to the members, which combined movement operates to 45 produce a type gradually and by a series of reductions and to accomplish the coincident 50 working out of the excess material. This subsidiary motion operates in conjunction with the aforesaid transverse feeding movement to force excess material away from the adjacent type—that is, crosswise or laterally of 55 the blank—and for further protecting the already-formed type I preferably use a wall or plate adapted to enter into the comparatively narrow space between the finished type and the material under the working die, 60 where it is located during the type-forming operation, serving as a retaining surface against which the moving material or flowage is received and by which its motion is directed. Such wall, it is evident, so far as the 65 purposes it fulfills are concerned, may be

separate from the die and operated independently thereof, but I find it convenient to attach it to the die and operate the two as a unit.

The foregoing subsidiary movement operating to gradually form a type and work the excess material outward transversely or crosswise of the blank preferably reverses in direction alternately, for the reason that such alternating motion is conveniently attained 70 and best adapted to produce a symmetrically-formed type. In other words, a relative oscillatory motion is imparted to the members (the die and the blank) during the period of type-forming, and for the production of this 75 relative movement I find it convenient to oscillate the blank by imparting such motion to a suitable work-holder in which the blank is supported. The operation of forming a type is thus performed by the die while in contact 80 with the typebar-blank and during the feeding of the blank toward the die or vice versa, the die operating to roll excess material side- 85 wise of the blank as the result of the oscillatory and feeding motion independently of the 90 making of a space in advance of the type. The direction, rapidity, extent, &c., of these movements—that is, the transverse feeding movement and the oscillatory movement—and the relation of these various factors to 95 each other, as well as the relation of the two specified movements one to the other, may be varied in any desired manner. The duration of the oscillatory movement may be embraced, for instance, within the limits of the 100 period during which the members are fed toward and against each other, but preferably the oscillation will commence after the type has been partially formed and cease just before the feeding movement terminates. 105 Furthermore, both movements may be uniform throughout their whole duration, or either may be varied, or they may both be varied.

With respect to an appropriate interrelation, I have found good results to follow from a gradual reduction of the speed of the transverse feeding movement during the later stages of such movement accompanied by a concurrent oscillatory motion decreasing in 110 amplitude or swing during the later stages of the feeding movement, ceasing altogether just prior to the termination of the latter movement. Such particular mode of operation is set forth more fully in my applications, 115 Serial Nos. 740,512 and 740,673, filed on the 16th day of December, 1899, and the 18th day of December, 1899, respectively.

It will be noticed in Fig. 4, which represents a die in contact with the blank at a late 120 stage in the type-forming operation, that the mass under the die is integrally connected with the unoperated-upon portion of the edge of the blank, which therefore affords a support for the type-blank while it is being 125 130

wrought to shape—that is to say, the portion or segment of the edge of the blank under the working die is, in this instance supported endwise of the blank by a wall or plate on one side and the stock of the blank on the other.

Instead of preliminarily treating the blank by trimming its edge longitudinally to remove a portion of the surplus material and thereby permit the sinking of the die into the blank without its meeting with a resistance to its motion sufficient to destroy or injure the type within the die, I may employ for the same purpose a path or surface of least resistance predetermined in position and along which flowage may take place with comparative facility.

The flowage induced by the type-formative stresses of the working die naturally takes place along the line of least resistance and these stresses have a tendency to detrimentally affect a finished type within the flowage radius of the forming type, for such sphere of disturbance extends ordinarily some distance beyond the narrow space between the letters of a word as words are ordinarily composed and spaced. Even though a wall is provided at the side of a die for the protection of a formed type, considerable pressure is exerted thereon by the metal under the compression of the die, and as this wall must be comparatively thin owing to the comparative narrowness of the space into which it is fed it is liable to spring and ineffectually confine the metal endwise of the blank. Furthermore, the formative stresses are liable to be transmitted under its lower edge, and, if in the attempt to prevent this, the wall is made comparatively deep, measured in line with the depth of the blank, and is advanced into the edge of the latter to reach below the flowage radius, since the wall must have some width, however small it may be, and the blank manifestly opposing some resistance to penetration, stresses are created by the wall itself as it advances of greater or less magnitude which tend likewise to produce a distortion of a formed type or face. In any organized system, moreover, of forming a series of types consecutively along the edge of a blank where individual type-blanks are not preliminarily treated to correspond with the particular types to be formed therefrom and the various steps and motions incident to or required in the type-forming process are not adapted to individual types, some provision or mode of operation must exist for nullifying the distorting tendencies of those dies which complete their types above the common level of the types in the finished type-bar. This distorting tendency may be minimized, if not effectually eliminated, by inducing flowage along a predetermined and preformed path or surface of least resistance, as aforesaid, whereby the formative and other stresses, in so far as they are concerned

in building up and positioning a type-block surmounted by a finished face, occasion a movement along a path predetermined in position. The direction of this predetermined path or surface is such as to facilitate the flowage of the metal under the rolling, swaging, forging and other operations to which it is subjected, and as these operations tend to move the metal outward toward the sides of the blank this path or surface extends crosswise of the latter. Such surface is also located under at least a portion of the metal subjected to the type-formative action, and I find it convenient to form successive surfaces along the blank simultaneously with the production of types; that is, a surface is formed each time a type is produced, of a width, however, insufficient to injuriously weaken the integral connection of the type-block with the stock of the blank. This flowage path or surface is made most advantageously I find in advance of a type, and in carrying out my present invention I form the same by making the vertical cross-space which will ultimately separate the next consecutive type-block to be made and completed along the blank from the type-blank just finished or in process of completion sufficiently wide when first formed to enter into the field of the next type or character. That is to say, the aforesaid surface is most readily formed by making the space or slot at the end of the last-formed type wider than this space will eventually be when the next consecutive type is formed for making the next consecutive letter in the composition.

In carrying out the method as above referred to some of the type spaces will be filled more readily than will others, and here reference will be had to Fig. 3, wherein there are shown three letters and a punctuation character, two of the letters are relatively large and the impression face of these before the die cavities which make them are completely filled are carried down to a plane considerably below the printing or impression face of the letter "o" when this is completed, and the punctuation mark embodying a mere dot or period had to be carried to a less extent until its die cavity was filled and its impression face formed, consequently to get the impression faces upon the same plane some of the dies have to carry the already formed type down below the position at which it is finished until its impression face is carried to the common plane, and during such carrying down under pressure the lengthwise justification of the types upon the bar will also be effected.

It is obvious from the above description that, in so far as the respective formation of the types and these spaces are concerned, each space may be formed independently of or simultaneously with the formation of a type, and furthermore that these results

may be attained by separate and independent tools or devices. Thus, for instance, Figs. 4 and 5, which illustrate one mode of carrying out the present invention, represent the formation of a type by a die which operates to produce a type-block the line of whose connection with the stock of the blank extends the entire height of the type-block the space in advance and which serves to complete this type-block being formed subsequently to the completion of the type. For making this space I have shown a double-edged cutter *c*, (see Fig. 8, especially,) which is carried by a suitable cutter-bar or cutter-carrier 20 pivoted to an angle-lever 21 carried by or secured to a suitable shaft or stud 22 and operated in any suitable manner, as by means of an arm 23. The cutter *c* preferably has two cutting edges *c'*, *c''* in order that it may plane the stock in both directions as it is reciprocated back and forth in contact with the blank. At each semi-reciprocation of the cutter one or the other of its cutting edges will remove a portion of the horizontal surface of the blank and when the type-block is completely finished the space it forms should be somewhat wider than the width of the retaining wall or plate integral with the die, so that when a die is adjusted to form the next consecutive type the wall will not fill the entire space but will leave an empty portion adjacent to the inner face of the wall toward which the material may shift when under the compression of the die until it contacts with the face of that wall and the surface formed by the lower edge of the cutting tool. This surface, (see line *z*) which is represented as being inclined somewhat, due to the pressure of the material under the action of the die, forms the previously-described surface of least resistance along which flowage may take place when the die advances into the metal. Such a mode of forming types and typebars, involving the pre-forming of a surface of least resistance, is set forth in application Serial No. 57,934, filed April 29, 1901; renewed June 17, 1904, Serial No. 212,952, and refiled February 12, 1907, Serial No. 356,975, to which reference may be made for a more detailed description. Instead, however, of forming the space in advance of a type along the blank after the completion of the same, the space may be made coincidently with the making of the block by a tool or other instrumentality acting independently of the die and serving to remove the material simultaneously with the advance of the die, or such tool may be connected to and form an integral part of the die. Such an organization is set forth in Fig. 6, in which it will be noticed that both the wall *f* and the space-forming die or instrumentality *f'* are made integral with the

type-die, the wall, however, being somewhat narrower than the space-forming die for the purpose of providing a surface of least resistance, as above set forth.

Instead of employing the integral connection of the type-blank with the stock of the type-blank as a forward support to the mass under the working die, I may utilize a space-forming die or other instrumentality which forms this space in advance of the type and prior to the operation of the type-die, but which remains in such formed space during the descent of the die into the edge of the blank. This method of forming types is represented in Fig. 7, in which 18 represents the space-forming die located in 80 the space in advance of the type-block and designed to be independent of the type-forming die in its operation.

Having described my invention, I claim—

1. That improvement in the art of making type which consists in subjecting a type-blank to compression in contact with type-dies until the die-space is filled and the type completely formed, and continuing such compression in contact with the type-die 90 and at the same time shifting the position of the completed type.

2. That improvement in the art of making types which consists in imparting to one of the following members—namely, a blank 95 and proper type-dies—a rolling, compressing movement depthwise and crosswise of the blank while in contact with the other member and until each respective die-space is filled and the type completely formed, and continuing such compression in contact with the type-die until the type is properly aligned and concurrently justifying the completed type by shifting the position of the same.

3. That improvement in the art of making 105 a line of type which consists in rolling at successive intervals a blank in contact with proper type-dies until each respective die-space is filled and the types completely 110 formed, and continuing such rolling in contact with the type-die and justifying the completed type by shifting the position of the same.

4. That improvement in the art of making 115 a typebar having a line of type which consists in successively imparting to one of the following members—namely, a typebar-blank and a type-die—a rolling, compressing movement in contact with the other until the die-space is filled and the type completely formed, and continuing such rolling, compressing movement in contact with the type-die and until the type is properly aligned and at the same time shifting the position of the completed type longitudinally 120 of the bar.

5. That improvement in the art of making 125 a typebar having a line of type which con-

sists in successively imparting to one of the following members—namely, a typebar-blank and a type-die—while in contact with the other, a rolling movement in a cycloidal path the cusp of which is in such blank and thereby filling the die-space and completely forming a type, and compressing the completed type depthwise of the blank while in contact with the type-die for thereby shifting the position of the completed type longitudinally of the bar.

6. That improvement in the art of making types which consists in imparting to one of the following members—namely, a typebar-blank and a type-die—while in contact with the other, a rolling movement in a cycloidal path the cusp of which is in such typebar-blank and thereby filling the die-space and completely forming a type, and continuing such cycloidal movement while the completed type is in contact with a type-die for

thereby shifting the position of the completed type lengthwise of the blank.

7. That improvement in the art of making types which consists in subjecting a typebar-blank supported at opposite sides to compression in contact with a type-die until the die-space is filled and the type completely formed, and continuing such compression in contact with the type-die for longitudinally disposing the metal immediately supporting said type for thereby shifting the position of the completed type on the bar. 25

8. That improvement in the art of making a type bar which consists in serially forming the type and under compression shifting the position of the formed type. 30 35
